UNITED STATES PATENT OFFICE.

CHARLES M. GRAVES, OF NEW YORK, N. Y.

LOCKING DEVICE.

Application filed July 23, 1927. Serial No. 207,957.

This invention relates to a combination controlled locking device for locking automobile ignition systems, transmissions, etc., against theft or unauthorized operation.

5 According to this invention between a manual actuating device, such as a key or lever, and the actuated device, such as the ignition switch or transmission locking bolt, is interposed a displaceable actuating connecting member, which latter is thrown in or out of the actuating train by a combination control or other secret form of lock. In such an arrangement additional safety is secured by reason of having the combination lock 10 only control the displaceable actuating connecting member and not to directly control movement of the actuated member. In this invention, the manual actuating member is preferably the key of a cylinder lock, for 15 additional security, but the device cannot be actuated unless the operator possesses both the key and the combination. A further characteristic of this invention is that in case of temporary stoppages the ignition can be 20 thrown on and off by the key without locking the combination, yet when it is desired to lock the system the intermediate connecting member controlled by the combination lock can be readily disconnected from the 25 actuating train. Provision is further made for preventing disconnection of the actuating train when the ignition is on.

This application is a continuation in part of my copending application, Serial No. 35 164,153, filed January 28, 1927, entitled Locking device.

The invention is shown herein in several modified forms which will be understood from the description of the accompanying 40 drawings wherein,

Fig. 1 is a plan view of the preferred form adapted for use in connection with the ignition switch of an automobile.

Fig. 2 is a similar view with portions relating to the combination and key controlled means in section.

Fig. 3 is a rear elevation with certain parts broken away showing the device in a position in which the intermediate member is 50 disengaged.

Fig. 4 is a similar view showing the parts in the positions in which the intermediate member is engaged.

Fig. 5 is a longitudinal section through a 55 modified form of the apparatus taken on the line 5—5 of Fig. 6.

Fig. 6 is a front elevation of this modified form.

Fig. 7 is a detailed partial section through a form of cylinder lock used showing the 60 manner in which the operation of the key causes the movement of one of the members.

Fig. 8 is a partial longitudinal section through a modified form of the device adapted for use as a transmission lock.

Fig. 9 is a plan view of a still further modification in which bars or levers are used as engaging members instead of gears and showing the parts in their disengaged relation.

Fig. 10 is a similar view showing the parts in their engaged relation.

Fig. 11 is a rear elevation of the device shown in Figs. 9 and 10.

In the preferred form of the invention shown in Figs. 1 to 4, inclusive, the invention comprises a front plate 10, a back plate 11, connected by bolts 12, between which is disposed a casing 13. Ignition or other circuit binding posts 14 are provided. 15 is a lock 75 casing having a cylinder 16 operated by a key 17 constituting manual actuating means. A gear 18 is connected to the rear of the cylinder 16 to turn therewith. An intermediate gear constituting an intermediate combination controlled displaceable element, 19 is loosely mounted on shaft 20 and is normally disposed, as shown in Fig. 1, out of engagement with gear 18. The looseness of gear 19 on the shaft prevents it from being 80 used to drive gear 41 by turning knob 35. A combination device controls the meshing and unmeshing of intermediate gear 19, and comprises plates 21 and 22 spaced from each other by posts 23, between which are disposed a plurality of combination discs 24, 25 and 26, provided with the usual notches 27, 28 and 29 which are to be aligned to permit one end 30 of a pawl pivoted at 31 to enter the notches when aligned. The other end 90 of the pawl is provided with a pin 32 which when the notches are not aligned occupies the position shown in Fig. 3, but which when the notches are aligned will occupy the position shown in Fig. 4. In the position shown in Fig. 3, the pin 32 lies within the periphery 95 of gear 19 and back of the same as shown in Fig. 1, preventing the gear 19 from being meshed, whereas when the notches are aligned, the pin 32 is in the position shown 100 in Fig. 4 outside the area of gear 19, as shown in Fig. 2, and permitting the gear 19

to be meshed. A spring 33 attached to the pawl normally tends to project the end 30 of the pawl into the notches.

The shaft 20 projects through the front of the casing in the form of an enlarged head 34 and a knob 35. This head lies slidably in recess 36 in the face of a rotatable dial 37, which has a keyway 38 therein adapted to receive a pin 39 on the head 34, so that when the pin and keyway are engaged, the knob is keyed to the dial 37. The dial 37 is fastened to the combination disc 26. A spring 40 is disposed between the gear 19 and the plate 21 tending to keep the gear 19 out of engagement with the gear 18.

A gear 41 is disposed adjacent the gear 19 and fastened to a block of insulating material 42. This block carries a switch plate 43 and is mounted rotatably on shaft 44. The switch plate in one position is adapted to bridge contact members 45 and 46 connected to bind the binding posts 14 to close any suitable circuit such as the ignition circuit of an automobile. A pin 47 carried by the block in one position thereof will bear against a post 48 to limit the movement in one direction of the block and the gear 41. Attached to the outer face of the gear 41 is a detent plate 49 having an extension 50 which when the gear 41 is in a certain position will lie partially across the edge of gear 19 when gear 19 is in mesh between gears 18 and 41, as shown in Fig. 4.

In the operation of this form of the invention, assuming the parts to be in the position shown in Fig. 1, the combination is inoperative and the gear 19 is out of mesh. The head 34 is disposed in the recess 36 with pin 39 in keyway 38. The key 17 is withdrawn from the cylinder 16 and the switch plate 43 is not bridging the contact members 45 and 46. The extension 50 of the plate 49 is in the position shown in Fig. 3. The pawl is in the position shown in Fig. 3 with respect to the notches in the combination discs 24, 25 and 26. By rotating the knob 35 when in this position, a predetermined number of turns in one direction or another, in accordance with the combination, the discs will be successively moved in the usual manner to align the notches 27, 28 and 29 therein with each other. The alignment of the notches, as indicated in Fig. 4, will permit the spring 33 to pull the end 30 of the pawl into the aligned notches and move the pin 32 out of the area of gear 19, as indicated in Fig. 4. The knob 35 is now pulled forward against spring 40 to mesh gear 19 with gears 18 and 41. As the knob is thus pulled forward the pin 39 is withdrawn from groove 38 and the knob 35 is given a lateral turn to rest the pin 39 in a notch in the face of dial 37 so as to keep the gear 19 meshed even if the device is subjected to vibration.

The key 17 is then inserted in the cylinder 16 and turned to rotate gear 18 and through the gear 19, to rotate gear 41, moving the switch plate 43 to bridge the contacts 45 and 46. At the same time the plate 49 moves with the gear 41 and the extension 50 thereon extends over the edge of gear 19 when the switch is closed. Consequently the knob 35, even if turned to bring the pin 39 in line with keyway 38, could not be pushed in to disengage the gear 19, because of this overlap. The gear 19 cannot be disengaged until the key 17 has been moved back to its normal position, and by the consequent movement of the gears, having turned extension 50 to the position shown in Fig. 3, where it is clear of the periphery of gear 19. This prevents throwing out gear 19 with the ignition on. After this has taken place, the knob can be moved inward by spring 40, or pushed in to disengage the gear 19. The knob 35 by reason of being keyed to the dial, is then rotated to upset the combination, and disalign the notches in the combination discs, so as to move the pawl to the position shown in Fig. 3 with the pin 32 back of the face gear 19 to prevent it being drawn forward again until the pin is removed by operating the combination. The key 17 can only be withdrawn when brought back to entering position, and the combination is unset by turning the dial, which happens when the knob is in and the intermediate element consequently is out.

By the combination of devices described, a controlled or actuated element, such as the switch plate 43, is opened and closed manually by a device such as a key 17, through an intermediate disengageable member such as gear 19, which latter is secretly controlled by the combination lock device. Specifically, the latter device controls the bodily shifting of gear 19 to mesh and unmesh it, and by reason of the loose mounting gear 19, does not drive it to actuate either the controlled element, as switch 43, or the manual actuating element, as key 17.

In the modified form shown in Figs. 5 to 7 inclusive, 51 is a suitable support, such as the instrument board of an automobile; 52 is a casing containing the device and on which its parts are mounted; 53 is a flange permitting the attachment of the casing to the support; 54, 55 and 56 are gears, the gear 55, as shown, being normally out of mesh with the gears 54 and 56; 57 is a shaft movable with the gear 54 and carrying an arm 58 which when moved will bridge the contacts 59 to close an electrical circuit which may contain a battery 59^a and a solenoid 59^b which may be associated with a locking mechanism of the transmission gears.

60 is a shaft, of which one end loosely

supports the gear 55, the other end of which carries a graduated knob 61, having an inner bore in which a spring 62 is disposed, tending normally to move the knob 61 and the shaft 60 outwardly of the casing; 63 represents the casing of a cylinder lock of the type in which a barrel 63^a receives a key 64 having notches in its edge to co-act with spring pressed plugs such as 64^a in the usual manner to permit the barrel to be rotated (see Fig. 7); a shaft 56^a connected to the rear of the barrel 63^a fixedly supports the gear 56; 65 is a block fixedly mounted within the casing and having a notch or slot 66 in one edge; 67 is a sleeve disposed rotatably within a bore in the block 65 having a plate 68 at its inner end, said plate being provided with a notch or slot 69. The front end of the sleeve 67 is provided with a graduated dial 70 disposed against the front of the casing and between the casing and the knob 61. Fixedly mounted on the shaft 60 is a disc 71 having on one face thereof a stepped lug 72 provided with stepped portions 73 and 74.

In the modified form shown in Fig. 8, the casing 75 corresponds to the casing 52 and may be attached adjacent the casing 76 of the automobile transmission. The gear 77 corresponds to the gear 54 in Fig. 5 and gear 78 corresponds to the gear 55, which is attached in this case also to a combination lock device in the manner previously described. In this modification, however, the gear 77 instead of actuating a switch arm, such as 58, is adapted to actuate a rack member 79 mounted in guides 80 and 81 and projecting through an aperture 82 in the casing 76. The end of this rack member, in the form of a bolt, projects into a notch 83 in the bar 84 or other element associated with the transmission so as to prevent its movement in either direction.

In the operation of the device shown in Fig. 5, it is necessary to have the key and to know the combination. If the combination is known, the dial 70 is moved to the proper position bringing the slot 69 in alignment with the slot 66. The knob is then turned to the proper position bringing the lug 72 in alignment with these two slots and permitting the spring 62 to move the shaft forward and thus permitting the gear 55 to mesh with the gears 54 and 56, this meshing being permitted by reason of the fact that the stepped portions 73 and 74 of the lug 72 are in line with the slots 66 and 69 and can move therewith. The gears 54, 55 and 56 being in mesh, the introduction of the key 64 into the barrel 63^a of the cylinder lock will so align the spring pressed plugs 64^a as to enable the barrel to be rotated by the key. This rotation will turn the shaft 56^a and with it the gear 56. The movement of gear 56 transmitted through gear 55 to gear 54 will cause

shaft 57 to turn thus swinging the switch arm 58 into a position to bridge the contacts 59. To disconnect the device it is necessary to move the key to a position to withdraw it after which the knob is pushed inwardly and turned. The dial 70 is also preferably turned to disalign the slot 69 from the slot 66.

In the operation of the modification shown in Fig. 8, the procedure is as above with the key and the combination lock to mesh the gear 78 with the gear 77 and when the key is turned will cause the projection of the rack bolt 79 into the notch 83 of the portion 84 of the transmission and lock it. To withdraw this bolt, the key must be turned whereupon it can be removed and the combination unset as above mentioned.

In the modification shown in Figs. 9 to 11, inclusive, a lock without gears is shown. It comprises plate 85 supporting a cylinder lock 86 having a key barrel 87 from the rear end of which extends an eccentrically disposed pin 88. This pin projects into a slot 89 in a bar 90 slidably disposed against the rear face of the lock casing. A set screw 91 is screwed into the rear face of the casing 86 through a longitudinal slot 92 in the bar 90. The opposite end of the bar 90 is in the form of a tapered fork 93. This forked portion extends toward and is disposed on either side of a slidable shaft 94 of a combination lock device.

This combination lock device may be of any suitable type either of the type shown in Fig. 2 or the type shown in Fig. 5 and as illustrated comprises a knob 95 on the front end of the shaft and a slotted head 96 on the rear end thereof. Between the head 96 and the main portion of the shaft 94 is a reduced portion 97. The combination lock preferably comprises a plurality of combination discs such as 98, 99 and 100 which may be operated in the manner above described to permit the shaft thereof to be moved forward and backward.

The bar 90 is provided with an offset parallel portion 101 which extends through the slot in the head 96. A spring 102 on this offset portion is also disposed in the slot and tends to move the shaft of the combination lock forward when the combination is set. The other end of this offset portion is provided with a contact head 103 adapted to engage spring contact members 104 and 105 mounted on a post 106 and connected to any desired circuit.

In the operation of this modification, assuming the parts are in the position shown in Fig. 9 and in the full line position shown in Fig. 11, the switch is open and the combination is inoperative and the shaft 94 is moved inward so that the main portion of it is embraced by the forked portion 93 of the bar 90, the dimension of which is such

that the bar 90 cannot be moved forward by the introduction of a key in the cylinder barrel 87 until the combination has been set and the shaft 94 been drawn forward or moved forward by the spring 102 to the position shown in Fig. 10 where the reduced portion 97 of the shaft comes in line with the forked portion 93 and by reason of its small diameter will permit the key to move the bar forward. This movement of the bar will move the offset portion 101 forward engaging the contact head 103 with the spring means 104, and 105 closing the desired circuit. In this closed position of the circuit it will be observed that the shaft 94, see Fig. 10, cannot be moved backward because in this position with the circuit closed, the forked portion 93 of the bar 90 has been moved forward to the dotted position shown in Fig. 11 and is too small in its width for the shaft to pass through and consequently acts as a barrier until the key has withdrawn the bar and opened the circuit.

It will therefore be observed that in all these modifications the key cannot be operated effectively to close the circuit or to perform its function unless the combination has been set and the element controlled by the combination has been moved into the desired position.

Various modifications and changes may be made in the various details shown and described without departing from the scope of the appended claims.

I claim:

1. A locking device comprising a manually operated actuating member, a combination controlled element, a member to be actuated, means controlled by the combination lock to prevent the actuation of one member by the other until the combination has been set, and means preventing disconnection of said members until the actuated member has been returned to normal position.

2. A locking device comprising a manually operated actuating member, a combination device, a member to be actuated, means controlled by the combination device to disconnect one member from the other until the combination is set, and means preventing the combination lock from being unset until the members have been returned to normal position.

3. A locking device comprising spaced members, a manually operated means for actuating one of said members, a third member normally out of engagement with the first and second members, a combination lock device associated with the third member and adapted when set to permit the third member to be moved into position to engage with the first and second members, and said third member being only actuated by said first member.

4. A locking device comprising spaced members, a key operated cylinder lock associated with one of said members for actuating the same when the key is operated, a third member normally out of engagement with the first and second members, and a combination lock device associated with the third member and adapted when set to permit the third member to be moved into position to engage with the first and second members.

5. A locking device comprising spaced members, a key operated cylinder lock associated with one of said members for actuating the same when the key is operated, a third member normally out of engagement with the first and second members, and a combination lock device associated with the third member and adapted when set to permit the third member to be moved into position to engage with the first and second members, the combination lock knob being mounted to move the third member into and out of engagement.

6. A locking device comprising spaced actuating and actuated members, an intermediate connecting member bodily movable into and out of actuating connection, and a combination lock controlling said intermediate member and having its knob movable when set to move said intermediate member into and out of connection.

7. A locking device comprising spaced actuating and actuated members, an intermediate connecting member bodily movable into and out of actuating connection, and a combination lock controlling said intermediate member and having its knob movable when set to move said intermediate member into and out of connection, said combination lock being incapable of moving said actuated member.

8. A locking device comprising the combination with a gear to be actuated, of a key-operated gear for actuating said first mentioned gear, and a combination controlled gear for connecting and disconnecting the other two gears.

9. A locking device comprising a member to be actuated, a manually operated actuating member normally disconnected therefrom and an intermediate combination controlled connecting member adapted to be interposed between the first two members only when the combination is set, to permit the actuation of the one member by the other.

10. A locking device comprising spaced gears, manual means for operating one of said gears, a third gear normally out of mesh with the first and second gears, a combination controlled means associated with the third gear and adapted when set to permit the third gear to be moved into posi-

tion to mesh with the first and second gears, and means for moving said third gear into said position as soon as the combination is set.

- 5 11. A locking device comprising spaced members, a key-operated cylinder lock associated with one of said members for actuating the same when the key is operated, a third member normally out of engagement 10 with the first and second members, a combination lock device associated with the third member and adapted when set to permit the third member to be moved into position to engage with the first and second members, 15 and means for moving said third member into said position as soon as the combination lock is set.

12. A locking device comprising an actuating gear, a key-operated cylinder lock associated with said gear for actuating the same an actuated gear, an intermediate gear normally out of engagement with the actuating and actuated gears, a combination lock device associated with the intermediate gear 25 to be moved into position to engage with the first two mentioned gears, and spring means adapted to move said intermediate gear into said position.

13. A locking device comprising an actuating member, an actuated member, means for moving the actuating member, an intermediate member normally out of engagement with the actuating and actuated members, a shaft on which said intermediate member is loosely mounted, a combination lock element associated and movable with said shaft, a fixed combination element adjacent the shaft having a slot therein, a movable combination element adjacent the shaft and having a slot therein, said element adapted to be moved to align its slot with that in the fixed element whereby as the shaft is turned the combination lock element associated therewith can be moved into said slots permitting the intermediate member to engage with the actuating and actuated members.

- 45 14. A locking device comprising a mem-

ber to be actuated, a manually operated actuating member normally disconnected therefrom, an intermediate combination controlled connecting member adapted to be interposed between the first two members to permit the actuation of one member by the other, means controlled by the combination member to prevent the engagement of the intermediate member with the other two members until the combination has been set, and means associated with the actuated member to prevent the disengagement of the intermediate member after the combination has been set until the actuated and actuating members have been returned to their normal position.

50 15. A locking device comprising a manually operated actuating member, a combination controlled device associated with said actuating member, said device having operative and inoperative positions, said device in one position preventing the movement 55 of the actuating member, means permitting the movement of said device to the other position when the combination is set to permit the movement of the actuating member, and means for preventing the return 60 of the device to its normal position after the combination has been set until the actuating member has been returned to its 65 normal position.

16. A locking device comprising a manually operated actuating member, a separated actuated member, an intermediate displaceable connecting member, a separate manually actuated combination device for controlling said connecting member, and means 70 controlled by the actuating member for preventing disconnecting movement of said connecting member by its manual controlling means except when said connecting member and the actuated member are in a certain 75 relative engaged position.

80 Signed at New York city, in the county of New York, and State of New York, this 19th day of July, A. D. 1927.

CHARLES M. GRAVES.
